Attorney

UNITED STATES PATENT OFFICE.

FRANK O. ARMSTRONG, OF ALTAMONT, KANSAS.

STRAW-BURNING DEVICE.

Application filed April 2, 1924. Serial No. 703,739.

To all whom it may concern:

Be it known that I, FRANK O. ARMSTRONG, a citizen of the United States, residing at Altamont, in the county of Labette and State of Kansas, have invented certain new and useful Improvements in a Straw-Burning Device, of which the following is a specification.

This invention relates to new and useful improvements for use in connection with burning straw, and has for its principal object to provide a simple and efficient means for regulating the burning of the straw when the same is deposited in a stove or furnace.

A further object of the invention is to provide a device of the above mentioned character, which includes a gravity actuated weight for placing a pressure on the straw when the same is in a stove, whereby the straw will be caused to burn more evenly and steadily.

A still further object of the invention is to provide a device of the above mentioned character, which may be conveniently and easily placed in position upon a stove without interfering with any of the parts thereof, means being provided for holding the device in an inoperative position while straw is being placed in the stove previous to the burning of the same.

A still further object of the invention is to provide a device of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification, and in which like numerals designate like parts throughout the same—

Figure 1 is a side elevation of a stove showing the shaft actuating means and the manner in which the straw and weight therefor are arranged within the stove,

Figure 2 is a vertical section through the stove with my attachment in position thereon, and

Figure 3 is a transverse section taken approximately on line 3—3 of Figure 1.

In the drawing wherein for the purpose of illustration is shown the preferred embodiment of my invention, the numeral 1 design-

nates a stove of any well known construction which is provided with a door 2 for depositing the straw in the stove, and the numeral 3 designates the door to the fire box, the same being of the usual construction and a further description of the same is not thought necessary for the purpose of carrying out the object of the present invention.

Extending transversely through the top of the stove 1 is the shaft 4. The shaft is journaled in any suitable manner in the opposed sides of the stove and carried on one end of the shaft on the outer side of the stove 1 is the ratchet wheel 6, a handle 5 being carried by the outer end of the shaft 4 adjacent the ratchet wheel 6 for the purpose of actuating the shaft. A suitable pawl 7 is pivotally supported on the stove 1 and cooperates with the ratchet wheel 6 in the manner as will be hereinafter more fully described.

Secured at one end to the intermediate portion of the shaft 4 is the chain 8, and the opposite end of the chain carries thereon the weight 9 which is in the form of a circular plate and is provided with a plurality of spaced apertures 10 in the manner clearly illustrated in Figures 2 and 3 of the drawing.

In use, the handle 5 is rotated so that the chain 8 will be wound around the shaft 4 raising the weight 9 to the top of the stove and the straw to be burned which comprises or consists of stalks of any grain plant that has been separated from the grain in a threshing machine, and usually the stalks are baled and when the straw is to be burned in the stove, the same is removed from the bale and deposited through the opening in the stove. After a certain quantity of straw has been deposited in the stove, the pawl 7 is released from engagement with the ratchet wheel and the weight 9 will by gravity descend in the stove, and will rest on the top of the straw deposited therein. The weight will cause a pressure to be placed on the straw so that the same may be caused to burn more evenly and steadily, and the openings 10 will provide a means for preventing the possibility of the smothering or smoking of the straw, thereby permitting the straw to be efficiently burned.

As the straw is burned, the weight will descend until all of the straw has been burnt, and the handle 5 is then actuated to again raise the weight 9 to the top of the stove, the pawl 7 holding the same against down-

ward movement therein, so that the stove may again be filled with straw to be burned, and the operation of the weight again repeated.

It will thus be seen from the foregoing description, that an attachment has been provided for use in connection with a stove whereby straw may be burned in an easy and efficient manner, the provision of the weight providing a sufficient pressure to cause the straw to be steadily burned. The simplicity of my device furthermore enables the same to be easily placed in position on any stove or furnace and will not require the alteration of the same in order to support the device in an operative position.

While I have shown the preferred embodiment of my invention, it is to be understood that various changes in the size, shape and arrangement of parts may be resorted to without departing from the spirit of the invention and the scope of the appended claim.

Having thus described the invention, what I claim is:—

25 A straw burning device of the class de-

scribed comprising a shaft adapted to be mounted for rotation in the upper portion of a stove, a hand crank connected to one end of said shaft, a ratchet wheel connected to said shaft, a pawl adapted for cooperation with the teeth of said ratchet wheel, a gravity lowered follower-weight adapted to be disposed for vertical movement within the body of the stove, said weight being of discular form and provided with a plurality of apertures and being of a predetermined diameter with respect to the body of the stove in which it is placed whereby to provide space between itself and the wall of the stove body, and a supporting and hoisting chain wound at its upper end upon said shaft and connected at its lower end to the center of said weight, whereby to permit free swinging of the latter so as to permit it to rest upon a burning fire of irregular form.

In testimony whereof I affix my signature.

FRANK O. ARMSTRONG.
